OF NEW YORK, N. Y., A CORPORATION OF NEW YORK**

TYING STRAND OR STRIP

Application filed January 17, 1931. Serial No. 509,525.

This invention relates to a tying strip or strand for use in tying various kinds of packages and merchandise.

In tying packages containing personal gifts, and in the cases of certain kinds of merchandise such as confections, for example, it is highly desirable to use a tying element possessing qualities and characteristics which give the package an attractive appear-

10 ance and yet the tying elements must be capable of being tied in a knot and should possess sufficient strength to enable handling of the gift, package or merchandise. Many manufacturers imprint their name or adver-

15 tising matter on the ribbons of various material, usually textiles, as such ribbons are the most widely used due to the fact that they are available in various materials, colors, and usually possess the required strength.

20 Substitutes for textile ribbons have been suggested and tried but not with complete or entirely satisfactory success due largely to the fact that such substitutes as have been proposed heretofore are not readily tyable

25 in knots and are not susceptible to imprinting of advertising matter.

This invention provides a novel and highly desirable tying element embodying and possessing the desirable qualities and characteristics of textile ribbons and certain advantages thereover which will become apparent during the course of the detailed description. One of the principal advantages of this invention is the great saving in cost and labor 35 in the production of the article.

In the accompanying drawing the tying element is shown on a greatly enlarged scale as the material is so thin that clear illustration on an exact scale would be practically impossible.

40 Fig. 1 is a perspective view of a spool with the tying strand or strip wound thereon and held in position by an adhesive element.

45 Fig. 2 is a fragmentary perspective view of one form of the invention with a portion of the element in elevated position.

Fig. 3 is a sectional view on the line 3—3 of Fig. 2.

50 Fig. 4 is a fragmentary perspective view

similar to Fig. 2 showing another form of the invention.

Fig. 5 is a sectional view on the line 5—5 of Fig. 4.

Fig. 6 is a fragmentary perspective view 55 of another form of the invention.

Fig. 7 is a central vertical sectional view through Fig. 6; and

Fig. 8 is a central vertical sectional view 60 of a modification of the form of the invention shown in Figs. 6 and 7.

Referring to the drawing, the numeral 10 designates a spool upon which is wound a tying strand or strip 11 embodying my invention and which is held in wound position on 65 the spool by the adhesive strip 12, one end of which is secured to the end of the strip 11 after which it is wound around on the strip and secured by an adhesive agent thereon against a portion of its own surface. This figure 70 merely illustrates how the strip or strand can be applied in the same manner as a textile ribbon to a spool for convenient merchandising.

Referring to Figs. 2 and 3, the strip 11 comprises a sheet of flexible transparent material such as "celophane" which is folded upon itself to form a 3-ply flat, flexible, transparent tying strip. An adhesive agent is applied between the folds as at 13 to hold the 80 adjacent surfaces of the folded portions tightly together. I preferably employ a transparent adhesive agent in the production of a transparent tying strip.

I have found in practice that the strip produced in the manner just described is very flexible and surprisingly tough. It will be noted that although two of the plies of the flat flexible transparent tying strip are rigidly held together by the transparent adhesive, 85 the other plies are not adhesively connected together and as a result may slip relatively to one another. It can be passed around a package in the same manner and with much facility as any flexible tying elements known 90 or used at the present time, and tied into a very tight knot without cutting itself. After the knot is tied a pull with considerable force on any portion of the strip will not break it, 95 and although I have not made actual test to 100

determine the exact amount of weight which the strip will support, I am satisfied that it will serve all of the purposes for which decorative ribbons and advertising ribbons are now used.

Referring to Figs. 4 and 5, the strip 14 is the same in character and construction as that shown in Figs. 2 and 3, but in this embodiment of the invention a flexible strip 15 of tissue or other paper or material is inserted between two of the folds of the strip 14. This embodiment of the invention affords the manufacturers means of exhibiting their name or other advertising matter by printing 10 the same on the insert 15, it being understood that the very thin and transparent material from which the incasing strip 14 is made acts as a protective medium for the printing or printed matter which shows clearly therethrough. In this embodiment of the invention the strip 15 gives added strength 20 to the tying strip or strand in proportion to its own strength, which can be varied by the choice of the material used.

In Figs. 6 and 7 I have shown a modification of the invention in which the flexible transparent sheet is folded over two parallel threads 18 with the flaps 19 incasing and holding the threads in place along the marginal edges of the tying strip. The flaps 19 are held to the face of the strip 17 by an adhesive as described in connection with Fig. 2. This form of the invention affords a very 30 novel and attractive tying element as there is a wide field for selection of colors either blending or contrasting in the cords and the strip material, so that very artistic effects 40 can be had, it should be apparent that the cords will impart to the tying element great strength without affecting its flexibility and adaptability to tying.

In Fig. 8 I have shown a modification resembling a combination of all of the other figures in which the transparent flexible material 20 is folded twice with overlapping 45 portions similar to the construction of Fig. 2 and with reinforcing or decorating threads 21 similar to Fig. 6. I wish to call attention to the fact that it is possible to insert any 50 desired number of threads in any desirable relative positions to produce various effects and designs.

In every form of the invention above described, it is possible to vary the number of 55 folds to more or less than those shown and to produce the tying strip in sizes and dimensions suitable to a required purpose.

While I have herein referred specifically 60 to a product known upon the market as "cellophane", which is a trade name for a well known material, having a cellulose base, I 65 wish to be understood as not limiting myself to this particular material, as other materials of a like nature, and which may be transparent or semi-transparent, may be employed

for the purpose, without departing from the spirit of the invention. I prefer to employ materials of the kind stated, and which may be clear or colored.

I have found very artistic and attractive 70 effects may be secured by employing a strip and a filler of contrasting color or colors, and this I consider to be an important feature of the invention. These artistic effects are due, in part, to the color or colors, and in part to 75 the effect produced by the transparent nature of the folded outer sheet, for example, when a sheet of clear transparent material is employed for the outer sheet, and the filler consists of white sheets, the finished product has 80 a silver like appearance.

Various other effects may be produced 85 where the outer sheet is tinted one color, and the filler has a different or contrasting color, and where threads of various colors and combinations of colors are used.

I claim:

1. As a new product of commerce, a tying strand consisting of a flattened cylinder or tube formed from flexible transparent sheets 90 of synthetic cellulose material, substantially one-half of the wall of said tube being formed of a single layer of said cellulose material, and substantially the other half of the wall of said tube being formed by a double layer 95 of said cellulose material separated by a thin layer of transparent adhesive material, the said tube or cylinder being flattened so that a strip will be formed, one side of which will consist of the single layer of material and 100 the other side of which will consist of the triple layer of material, the inner walls of said tube or cylinder being substantially free of adhesive, so that when the tube or cylinder is flattened they may readily slip relative to 105 each other.

2. The strand of claim 1 in which a fibrous material is centrally positioned within a flattened tube or cylinder and contacts with the middle portion of the inside face of the single 110 wall, and with the central portion of the inner face of the innermost member of said triple wall.

3. The structure of claim 1 in which threads 115 of fibrous material are enclosed within the flattened tube and extend longitudinally along its opposite edges.

4. As a new product of commerce, a tying strand consisting of a flattened cylinder or tube formed from flexible transparent sheets of synthetic cellulose material, at least one-half of the wall of said tube being formed of a single layer of said cellulose material, and substantially the remaining portion of the wall of said tube being formed by a double layer of said cellulose material separated by a thin layer of transparent adhesive material, the said tube or cylinder being flattened so that a strip will be formed, one side of which will include the single layer of material and 120 125 130

the other side of which will include the triple layer of material, the inner walls of said tube or cylinder being substantially free of adhesive, so that when the tube or cylinder is flattened they may readily slip relative to each other.

Signed at New York city in the county of New York and State of New York this 16th day of January A. D. 1931.
